US00D990292S

(12) **United States Design Patent** (10) **Patent No.:** **US D990,292 S**
Sargent (45) **Date of Patent:** **** Jun. 27, 2023**

(54) **TROLLEY APPARATUS FOR SLACKLINE WEBBING**

(71) Applicant: **eBrands Global Oy**, Helsinki (FI)

(72) Inventor: **Nathan Thomas Sargent**, Oceanside, CA (US)

(73) Assignee: **eBrands Global Oy**, Helsinki (FI)

(**) Term: **15 Years**

(21) Appl. No.: **29/871,079**

(22) Filed: **Feb. 10, 2023**

Related U.S. Application Data

(63) Continuation of application No. 29/834,031, filed on Apr. 8, 2022, now Pat. No. Des. 977,950, which is a continuation of application No. 29/810,589, filed on Oct. 6, 2021, now Pat. No. Des. 961,369.

CLAIM

The ornamental design for a trolley apparatus for slackline webbing, as shown and described.

DESCRIPTION

FIG. 1 is a perspective view of a trolley apparatus for slackline webbing showing the new design;

FIG. 2 is a front view thereof;

FIG. 3 is a side view thereof;

FIG. 4 is a top view thereof; and,

FIG. 5 is a bottom view thereof.

The broken lines depict portions of the article that form no part of the claimed design.

1 Claim, 2 Drawing Sheets
